J. McKECHNIE,
VALVE GEAR OF INTERNAL COMBUSTION ENGINES.
APPLICATION FILED FEB. 27, 1920.

1,352,758.

Patented Sept. 14, 1920.

UNITED STATES PATENT OFFICE.

JAMES McKECHNIE, OF BARROW-IN-FURNESS, ENGLAND, ASSIGNOR TO VICKERS LIMITED, OF LONDON, ENGLAND.

VALVE-GEAR OF INTERNAL-COMBUSTION ENGINES.

1,352,758.

Specification of Letters Patent. Patented Sept. 14, 1920.

Application filed February 27, 1920. Serial No. 361,806.

To all whom it may concern:

- Be it known that I, JAMES McKECHNIE, a subject of the King of Great Britain, residing at Naval Construction Works, Barrow-in-Furness, in the county of Lancaster, England, have invented certain new and useful Improvements in or Relating to the Valve-Gear of Internal-Combustion Engines, of which the following is a specification.
- 10 This invention relates to the valve gear of internal combustion engines of the kind in which the exhaust and induction or inlet valves are operated by cams through cam levers which can be placed into and out of 15 action, separate cams being employed for ahead running and astern running, which cams are brought into and out of operation by axial displacement.

According to the present invention the 20 means for axially displacing the cams comprises a pivoted slotted lever having a slot and pin connection to a servo motor or hand actuating mechanism and so interconnected with the mounting of the cam levers that, 25 on reversing the engine, the levers are first moved clear of the cams, the cams are then moved by the aforesaid slotted lever axially into their new position and the levers are finally brought into their operative positions 30 in contact with the reverse cams, the lever slot being shaped to provide for such succession of operations. The cam shaft itself may be axially displaceable with the cams and may carry two pairs of cams, one pair 35 for each of the cam levers, and a crank or like connection to the cam levers may be employed to raise and lower them from and on to their cams, respectively before and after the movement of the pivoted lever.

40 In order that the said invention may be more clearly understood and readily carried into effect the same will now be described more fully with reference to the accompanying drawings, in which:—

45 Figure 1 is an elevation of apparatus embodying this invention, and

Fig. 2 is an elevation of the same apparatus at right angles to Fig. 1, with a portion shown in section.

50 A is the sliding cam shaft on which are mounted the ahead and astern cams B, B', two pairs of such cams being shown, one pair for the inlet valve and the other pair for the exhaust valve. C, C' are the cam 55 levers carrying rollers c which bear upon

the cams B, B', the levers being mounted on the eccentrics d on the fulcrum shaft D. E, E' are the valve levers for the inlet and exhaust valves F, F', the valve levers being connected by the rods e to one arm of the 60 cam levers C, C'. G is the pivoted lever operating the cam shaft A through the fork g and collar a, the lever G having the slot g' at its lower end, the slot having two portions radial to the pivot g² with a sloping connecting portion. H is a rack on the end of a shaft h actuated by the servo motor J provided with the buffer oil cylinder or dashpot K, the servo motor having a reversing valve j controlled by the reversing 65 handle j', air under pressure being admitted through the inlet pipe j² and passed to either end of the cylinder J, as required, through the pipes j⁴. For convenience, the valve j is mounted on the oil cylinder K, which is 70 provided with a by-pass valve to regulate the dashpot action.

The rack H gears with a pinion l on the shaft L which is provided at its end with a crank l' connected by the rod l² to a lever 80 d' on the fulcrum shaft D. The pinion shaft L can also be operated by the reversing hand wheel M through the shaft m, clutch m' and bevel gearing m², the hand wheel being brought into action by means 85 of the clutch when required, the servo motor, however, being usually employed.

The rack H is mounted on the face of a slide h' which slides upon the block h² mounted on the engine casing N and carries 90 the roller or pin h³ extending through the slot g' of the lever G, the pin connecting the front and back parts of the slide between which the end of the lever extends. The mounting of the pin at both ends prevents 95 any risk of bending the pin on operating the lever. The pivot g² of the lever G is carried in the brackets g³ mounted on a part of the casing N. The cylinders J and K are carried by the brackets j² and k 100 mounted on the face of the casing, the cylinder J being supplied with air under pressure through the reversing valve j.

The reversing operation is carried out as follows with the parts in the position 105 shown:—The reversing handle j' is turned to allow the air to pass through the valve j into the servo motor cylinder J so as to lift the rack shaft h with the slide h' and rack H. The initial movement of the rack acting 110

trough the pinion *l* turns the shaft *L* and the crank *l'* so as to rotate the fulcrum shaft *D* and lift the rollers of the cam levers *C*, *C'* from the cams *B*, *B'*. During the first part 5 of this operation the pivoted lever *H* is not operated as the roller *h*^s of the slide *h'* moves through the lower radial portion of the slot *g'*. As soon as the middle portion 10 of the slot is reached the lever *G* turns and causes the cam shaft *A* to slide and to bring the astern cams *B'* under the rollers *c*. The final portion of the movement leaves 15 the pivoted reversing lever *G* unaffected, the roller *h*^s moving in the second radial portion of the slot *g'* but the continued movement 20 of the fulcrum shaft *D* brings the eccentrics *d* again into the position in which the rollers *c* are brought down upon the cams so that the second pair of cams *B'* are now operative for the reversing of the engine.

On reversing the operation of the servo motor so as to lower the rack and slide the reverse operation on the cam levers takes 25 place, the eccentrics first raising the levers from the cams *B'*, the cam shaft being then shifted back into the position shown in Fig. 1 and the continued movement bringing the cam levers again into operation on the 30 cams *B*.

In case the servo motor is out of order, the hand reversing mechanism can be brought into operation by closing the clutch *m'* and turning the hand wheel *M*, whereupon 35 the pinion shaft *L* effects the movement of the fulcrum shaft *D* and at the same time through the pinion and rack moves the slide *h'* to operate the reversing lever *G*. Instead, however, of employing a 40 mechanical hand gear, an oil pump can be used operating the gear through the oil buffer cylinder *K*, using the latter as a motive power cylinder, in which case the bypass valve in the buffer cylinder would be 45 closed and one in the air cylinder *J* would be opened.

What I claim and desire to secure by Letters Patent of the United States is:—

1. In reversing valve gear for internal 50 combustion engines, axially displaceable forward and reverse cams, a valve lever adapted to coöperate with the said cams, a pivoted slotted lever for effecting the axial displacement of the cams, means engaging 55 in the lever slot for turning the said lever through an angle for reversing purposes and means associated with the said slotted lever for raising the valve lever clear of the cams during their sliding movement.

2. In reversing valve gear for internal 60 combustion engines, axially displaceable forward and reverse cams, a valve lever adapted to coöperate with the said cams, a pivoted cam displacing lever provided with 65 a slot comprising two radial portions and

an inclined connecting portion, a sliding lever operating member engaging in the said slot and means associated with the said slotted lever for raising the valve lever clear of the cams during engagement of the said operating member with the inclined portion of the said slot. 70

3. In reversing valve gear for internal combustion engines, axially displaceable forward and reverse cams, a valve lever 75 adapted to coöperate with the said cams, a pivoted slotted lever for effecting the axial displacement of the cams, means engaging in the lever slot for turning the said lever through an angle for reversing purposes, a 80 shaft gearing with the said lever turning means, a crank arm on the said shaft and a connection from the arm to the valve lever whereby the latter is raised from the cams during their sliding movement. 85

4. In reversing valve gear for internal combustion engines, axially displaceable forward and reverse cams, a valve lever adapted to coöperate with the said cams, a pivoted slotted lever for effecting the axial 90 displacement of the cams, means engaging in the lever slot for turning the said lever through an angle for reversing purposes, a servo motor actuating the lever turning means and means also actuated by the said 95 servo motor for raising the valve lever clear of the cams during their turning movement.

5. In reversing valve gear for internal combustion engines, axially displaceable forward and reverse cams, a valve lever adapt- 100 ed to coöperate with the said cams, a pivoted slotted lever for effecting the axial displacement of the cams, means engaging in the lever slot for turning the said lever through an angle for reversing purposes, a 105 servo motor adapted to operate the said turning means, hand operated mechanism adapted to be connected up at will to the said turning means and means operable by the servo motor and the said hand operated 110 mechanism whereby the valve lever is raised clear of the cams during their sliding movement.

6. In reversing valve gear for internal combustion engines, axially displaceable 115 forward and reverse cams, a valve lever adapted to coöperate with the said cams, a pivoted slotted lever for effecting the axial displacement of the cams, a sliding rack eng- 120 gaging in the lever slot, a reversing servo motor adapted to actuate the sliding rack, a shaft having a pinion gearing with the rack and a crank connection from the said shaft to the valve lever, for the purpose specified. 125

7. In reversing valve gear for internal combustion engines, axially displaceable forward and reverse cams, a valve lever adapted to coöperate with the said cams, means for raising the valve lever clear of 130

the cams, a pivoted lever effecting the axial displacement of the cams and a connection between the said pivoted lever and the valve lever raising mechanism, whereby the said pivoted lever is operated for reversing purposes after the valve lever has been raised clear of the cams and the said valve lever

is again brought into operative position on the completion of the axial displacement of the cams.

In testimony whereof, I affix my signature.

JAMES McKECHNIE.
